CLAIM

The ornamental design for a user interface, as shown and described.

DESCRIPTION

FIG. 1 is a top perspective view of a user interface;
FIG. 2 is a front view of the user interface of FIG. 1;
FIG. 3 is a top view of the user interface of FIG. 1;
FIG. 4 is a left side view of the user interface of FIG. 1; and,
FIG. 5 is a right side view of the user interface of FIG. 1.
Portions of the drawings shown in broken lines form no part
of the claimed design.
